(57) **CLAIM**

The ornamental design for an assembled floor module, as shown and described.

DESCRIPTION

FIG. 1 is a front view of an assembled floor module showing my new design;

FIG. 2 is a back view thereof;

FIG. 3 is a left side view thereof;

FIG. 4 is a right side view thereof;

FIG. 5 is a top view thereof;

FIG. 6 is a bottom view thereof;

FIG. 7 is a perspective view thereof;

FIG. 8 is an enlarged perspective view showing the left front corner in the FIG. 7;

FIG. 9 is an enlarged perspective view showing the right front corner in the FIG. 7; and,

FIG. 10 is a perspective view showing the assemblage of the assembled floor module.

The assembled floor modules shown by broken lines are for the purpose of illustrating that form no part of the claimed design.
